UNITED STATES PATENT OFFICE.

ALEXANDER R. HAGNER, OF HAGERSTOWN, MARYLAND.

GRAIN-DRYING APPARATUS.

No. 799,901.

Specification of Letters Patent.

Patented Sept. 19, 1905.

Application filed November 21, 1904. Serial No. 233,587.

To all whom it may concern:

Be it known that I, ALEXANDER R. HAGNER, a citizen of the United States, residing at Hagerstown, in the county of Washington and State of Maryland, have invented certain new and useful Improvements in Grain-Drying Apparatus, of which the following is a specification.

This invention relates to a drying apparatus for grain-bins, and has for its object to provide a simple device by means of which air may be thoroughly distributed through the grain while the latter is being agitated or churned and the drying operation thereby quickly accomplished.

The accompanying drawings illustrate the invention, in which—

Figure 1 illustrates a central vertical section through the drying apparatus and the air-distributing cylinder, the section being taken on the line 1 1 of Fig. 5. Fig. 2 is a similar view, on an enlarged scale, of one end of the air-distributing cylinder and the adjacent supporting-wall. Fig. 3 illustrates a vertical section on the line 3 3 of Fig. 6 and shows a side elevation of one of the circumferential air-chambers having a plurality of air-compartments. Fig. 4 illustrates a perspective view of one of the radial supports or plates for separating the compartments in the air-chambers and to which the side plates or screws are attached. Fig. 5 illustrates a sectional plan view of the apparatus. Fig. 6 illustrates a perspective view of the air-cylinder detached and the circumferential air-chamber, and Fig. 7 illustrates a detail side elevation of the agitating shafts and arms at the side of said chamber.

Referring to the drawings by letters, A designates a receptacle of any suitable construction, but in the present instance having a hopper-receptacle a , provided with a discharge-outlet a^2 , which is controlled by a slide a^3 . A bottom a' is provided, which is interposed between the main receptacle and the hopper-receptacle.

At opposite sides the walls of the receptacle A are provided with openings b , and a bearing-plate b' is secured to said walls over said openings, and each plate is provided with an opening b^2 through which air may pass. A horizontal shaft c is supported at opposite ends in said bearing-plates b' , and said shaft is provided with a pulley c^3 , which may be revolved in any suitable manner. A plurality of arms c' are suitably carried by said

shaft and said arms support fan-blades c^2 , in the present instance four in number, which revolve with said shaft.

A hexagonal frame comprises two end plates d , each of which has a center perforation d' and a plurality of horizontal rods d^2 , angular in cross-section, which connect said plates. A wire-sheet screen e is wrapped in sections around the hexagonal frame and forms an air-distributing cylinder e' , in which the fan is located. By reference to Fig. 1 of the drawings it will be seen that this distributing-cylinder e' extends from one side of the main receptacle to the other and its ends terminate in the circular openings b in the receptacle-walls, so that the perforations d' in the end plates adjoin or are at the side of the openings b^2 in the bearing-plate b' . By means of this arrangement air may be drawn through the openings b^2 and perforations d' to the interior of the distributing-chamber in which the fan-blades revolve.

The wire-sheet screen e is wound in sections around the horizontal rods d^2 , as clearly seen in Fig. 6, with an annular space e^2 between each two adjacent sections. This annular space is to be utilized to permit the air from the interior of the fan-cylinder e to be directed readily through the receptacle A, as will now be described.

Projecting outwardly from each of the rods d^2 is a support or division-plate f , which in the present instance has a square perforated lower end, so as to fit over the square rod to prevent turning thereon, so that said supports or plates will be rigidly maintained in a radial position with respect to the fan-shaft c . The outer projecting end of each division support or plate is provided with a lateral flange or flat face f' for a purpose to be presently described. In the drawings six horizontal rods are shown, and each is provided with radially-projecting division-plates.

A screen-band f^2 is passed around the outer ends of all the radial supports or division-plates and rests on the flat faces, and flat sheet-screens f^3 and f^4 have hexagonal central perforations g , which fit snugly around the cylinder e' at opposite sides of the divisional plates and form a circumferential or annular chamber with a plurality of radially-arranged air-spaces g' between each two divisional plates. These air-spaces, it will be understood, are open at the inner ends between the horizontal rods d^2 and are in direct communication with the interior of the fan-cylinder, so

- that air may pass freely from said cylinder into each radial air-space. It will also be noted that the divisional plates being imperforate entirely separate one air-space from another.
- 5 By reference to Figs. 1, 6, and 7 it will be seen that the fan-cylinder in the present instance is provided with three sets of radial air-spaces, each set being spaced from the other, so as to form a plurality of vertically-extending grain-spaces g^2 . In practice the air-spaces are about six inches in width. As the grain is discharged into the receptacle A it will fill up from the bottom a' in the spaces g^2 and around the screen e of the fan-cylinder, and the grain contacting with the screens e , f^2 , f^3 , and f^4 will quickly become dry, while the grain farther away from said screens would not receive the direct air, and would therefore be comparatively slow in drying.
- 10 In order to overcome this and enable practically the entire bulk of grain to be subjected to the direct air, I provide means for agitating the bulk and shifting the grain continuously, so that all of it may receive the benefit of the direct air-current and the entire bulk quickly dried out. This agitating device comprises a plurality of vertical shafts h , h' , h^2 , and h^3 . In the present instance these shafts are arranged in sets or vertical rows 15 and each row being parallel with the fan-cylinder and one shaft of each row extending vertically through one of the grain-spaces g^2 . As there are four grain-spaces, each row comprises four shafts.
- 20 As shown in Fig. 6, there are two rows of vertical shafts on each side of the fan-cylinder, the rows h and h' being on one side and rows h^2 and h^3 at the opposite side of said cylinder. The lower ends of all the vertical shafts project through the bottom a' of the receptacle and are supported in cup-bearings i on the lower side of said bottom. The upper ends of the shafts extend or project through a cover-plate i' , in which they have bearing, 25 and the projecting ends of all the shafts carry bevel-gears j . Horizontal shafts k , k' , k^2 , and k^3 extend, respectively, across the upper ends of the shafts h , h' , h^2 , and h^3 , and these horizontal shafts each carry four bevel-gears l , 30 which revolve in a vertical plane and are spaced so that those on each shaft will mesh with the bevel-gears j on the vertical shafts immediately below. The outer ends of the horizontal shafts extend beyond the side wall 35 of the receptacle A, and said ends each carry sprocket-wheels m . The shafts k' and k^2 are also provided with sprocket-wheels n , and a pulley o is also mounted on the end of the shaft k^3 , which in this instance becomes the 40 main shaft. A sprocket-chain P passes over the sprockets n and transmits motion from the shaft k^3 to shaft k' . A sprocket-chain P' connects the sprockets m on the shafts k and k' , and a like chain P^2 connects the sprockets m on the 45 shafts k^2 and k^3 . It will thus be seen that all

the horizontal and vertical shafts are driven by the pulley o on the shaft k^3 . The vertical shafts are provided with laterally-projecting arms q , and said arms are staggered so that the arms on one shaft will pass between the 50 arms on the next shaft in the same grain-space. By this arrangement of shafts and arms in each grain-space the grain will be thoroughly circulated and churned in said spaces, and air passing from the fan-cylinder 55 and radial air-spaces will quickly dry the grain.

Beneath each grain-space the bottom a' is provided with a slide r , which may be opened to allow the dry grain to discharge into the 60 hopper a and out through the outlet a^2 .

Grain may be fed to the receptacle by a hopper s entering the top.

It will be understood that the fan-cylinder e and radial wire-covered air-spaces g' are 65 stationary and that the fan-shaft c and blades c' are revolved therein, drawing air, which may be first heated, if desired, through the openings b' and perforations d' to the interior of said cylinder. The grain having been filled 70 into the receptacle over and around the cylinder and radial air-spaces, the air from the fan will pass through the perforations in the screens of which the cylinder and air-spaces are formed, and as the vertical shafts are 75 revolved the radial arms will move in a horizontal plane through the grain and churn or agitate the latter, so that practically all of the grain in the receptacle is subjected to the direct air-blast. It will thus be seen that the 80 drying of the grain may be quickly accomplished. After the grain is dry it will be discharged through the bottom slides and the receptacle again filled. It is obvious that the 85 air may be heated, if desired.

Having thus fully described my invention, what I claim as new, and desire to secure by Letters Patent, is—

1. The combination with a stationary grain-receptacle, of a stationary cylinder in said receptacle, annular air-chambers radiating from and extending entirely around said cylinder and in communication with the interior of the latter and means at the side of each chamber for agitating the grain.

2. The combination with a stationary grain-receptacle, of a stationary perforated cylinder in said receptacle, air-chambers extending entirely around said cylinder spaced from each other to form a plurality of grain-spaces and 110 revolvable agitating devices in each grain-space between each two air-chambers.

3. The combination with a stationary grain-receptacle, of a perforated cylinder in said receptacle, a plurality of circumferential chambers around and opening into the perforated cylinder and separated from each other to form vertical grain-spaces, the vertical walls of said circumferential chambers being perforated, and a plurality of grain-agitators in 125 130

said grain-spaces and extending in a direction parallel with and between the circumferential chambers.

4. The combination with a stationary grain-receptacle, of a stationary perforated cylinder in said receptacle and having openings which extend around the cylinder, parallel perforated walls extending at right angles from said cylinder at said circumferential openings and forming air-chambers, a fan on the interior of said cylinder and revoluble grain-agitators between said circumferential air-chambers. 30

5. The combination with a stationary grain-receptacle, of a stationary perforated cylinder in said receptacle, a plurality of stationary supports extending radially from said cylinder, perforated sheets at each side of said supports and extending circumferentially around said cylinder and forming radial air-spaces 40 between each two supports, and a plurality of shafts extending through the air-spaces at each side of the supports, and agitating-arms on said shafts. 45

6. The combination with a grain-receptacle, 25 of a perforated cylinder in said receptacle, parallel pairs of perforated sheets surround-

ing said cylinder and extending at right angles to said cylinder and each pair forming an annular air-chamber, which communicates with the interior of said cylinder, a fan in the 30 interior of said perforated cylinder, shafts extending through the receptacle between the adjacent annular air-chambers, agitating-arms on said shafts and means for revolving said shafts and arms. 35

7. The combination with a grain-receptacle, of a perforated cylinder in said receptacle, a fan in said cylinder, annular air-chambers surrounding said perforated cylinder and forming parallel grain-spaces, shafts arranged in 40 rows in said grain-spaces on each side of said perforated cylinder, agitating-arms on said shafts, shafts extending crosswise of the ends of each row of shafts, and means for transmitting power from said latter shafts to the 45 agitator-shafts.

In testimony whereof I affix my signature in presence of two witnesses.

ALEXANDER R. HAGNER.
